UNITED STATES PATENT OFFICE.

DOLPHUS TORREY, OF NEW YORK, N. Y.

LOCOMOTIVE AND TRAIN BRAKE.

SPECIFICATION forming part of Letters Patent No. 276,928, dated May 1, 1883.

Application filed March 20, 1882. Renewed March 27, 1883. (No model.)

To all whom it may concern:

Be it known that I, DOLPHUS TORREY, a citizen of the United States, residing in the city and State of New York, have invented an Improvement in Fluid-Brake Mechanism, of which the following is a specification.

My invention relates to a use and application of connected or associated cylinders having different sectional areas, the pistons of which are connected to the brake mechanism, and the ports of which are so connected with the boiler or other source of pressure-supply that the steam or other fluid may be admitted to either of the cylinders singly or coincidentally, whereby the stress of the braking apparatus is made of three degrees of intensity with one degree of steam-pressure in the boiler. Steam or other fluid is admitted to the cylinders preferably by means of a cock having several ways, and may be so arranged that the driver of the locomotive may, by turning the cock a slight distance, bring into use one cylinder, by turning the cock a little distance farther, the other one, severing the connection of the first cylinder, and, finally, by turning the cock farther yet, connect both cylinders and secure their power jointly. By this means it is in his power, with cylinders properly proportioned, to apply his brakes with a pressure of, say, two thousand pounds, four thousand pounds, or six thousand pounds—a matter of the greatest importance in the case of a locomotive, which at its different rates of speed calls for differing degrees of brake-pressure to obtain the best results. The mechanical arrangement is applicable to the use of air-brakes, either compressed or vacuum, and to the transmission of the stress to the brake appliance by means of water-rods or other, either rigid or flexible, mechanical connection for tension or compression. Two or more air-cylinders, having their pistons connected by a common rod, can be brought into separate or joint use by the application of the mechanical devices hereinafter set forth, so as to secure single, double, or treble degrees of power by the turning of the cock controlling the motor-fluid, and in a similar way with the cylinders, bags, or diaphragms of vacuum brakes.

To illustrate the preferred method of using my invention, the case is taken of an appara-

tus for the use of steam upon a locomotive to apply the brakes attached thereto. At any convenient place upon the locomotive are set the two steam-cylinders, preferably cast in the same axial line, with a solid head between them common to both. In these cylinders are two pistons attached to a common piston rod, which extends through one of the end heads to a connection with the ordinary brake rods, levers, &c. Steam is taken from the boiler of the locomotive and admitted to one end of one of the cylinders, or to both, as may be desired. Its expansion forces the piston-rod out, and thereby moves the brake attachments and applies the brakes. It should be understood that I do not limit myself to the use of two cylinders, as under circumstances likely to arise more may be desirable. I also contemplate the use in connection with these steam-cylinders of a hydraulic cylinder, which by means of connecting water-rods can effect an application of the brakes by means of appropriately-located cylinders.

In the drawings, Figure 1 is a longitudinal section of the connected cylinders. Fig. 2 is perspective view of the cock or valve on a larger scale. Fig. 3 is a longitudinal section of said cock or valve, also on a larger scale. Fig. 4 is a plan view of the entire surface of the cock or valve as if unrolled, showing the relative positions of the ports. Fig. 5 is a side view, on a smaller scale, of a locomotive and tender with the invention applied.

1 and 2 represent steam-cylinders of different areas, mechanically connected, and having a common piston-rod, 10, to which their respective pistons 11 and 12 are fixed, said piston-rod working through a packing in the common connecting-head of the two cylinders, 9c which head separates their chambers.

3 represents a hydraulic cylinder fitted with a piston, 13, which is fixed to the extremity of the same piston-rod, 10.

6 and 7 are steam-pipes leading from the cock or valve shown in Figs. 2 and 3, the pipe 6 opening into the cylinder 1, and the pipe 7 into the end of the cylinder 2, so that steam admitted through the respective pipes 6 and 7 will have the effect of impelling the rod 10 in one and the same direction, but with different degrees of force, determined by the relative

areas of the said cylinders. The pipe 28 communicates with the chamber 4 in the rear end of the cylinder 1 for releasing the brakes.

5 is the water-chamber of the hydraulic cylinder 3, and 9 a pipe or water-rod, through which the liquid is forced by the piston in said cylinder 3 in order to apply the brakes by communication with water or air cylinders in customary manner.

10 The piston-rod 10 may, if preferred, connect directly with chains, pitmen, and other common mechanical devices for actuating the brakes instead of with the hydraulic connection 3 5 9, as herein shown.

15 The cock or valve shown in Figs. 2 and 3 consists of a cylinder or casing, 14, having an inlet-pipe, 15, connected with it at any suitable point, a series of outlet-pipes, 6 7 8, and a discharge-pipe, 16. These may be in a vertical line, 20 as shown. The valve proper consists of a stem, 17, of skeleton form, carrying a shell, 18, fitted in the cylindrical casing 14, so as to communicate at its interior with the inlet-pipe 15, and having a number of ports, 19, 20, 21, and 25 22, in its periphery. The port 20 and the rear ends of ports 21 22 are in a vertical line. The ports 19 20 are so arranged that either may be brought to register with the steam-pipe 6.

21 is a port elongated circumferentially and 30 with one end in line with the port 20, while its other end is midway between the ports 19 and 20, so that when one end of said port 21 is brought into register with the pipe 7 steam will be discharged through the said pipe 7 35 alone; but by a further movement of the valve the ports 20 and 21 are brought in register with the respective pipes 6 and 7, simultaneously causing the delivery of steam through both.

40 22 is a port registering with the pipe 8, which connects with any suitable train-brake apparatus. For illustration, I have shown it terminating in an ejector-nozzle, 26, from which a pipe, 27, connects with a vacuum-brake, 29, 45 under the tender, and extends through couplings 30 to all the cars of a train in the usual manner. The port 22 is elongated, so that its extremities are in line with the respective ports 19 and 20, causing the train-brake to be 50 thrown on whenever the locomotive-brake is opened under either degree of pressure. The valve is further provided with a longitudinal groove, 24, in its periphery, by which, while the communication with the inlet-pipe 15 is 55 closed, all the pipes 6 7 8 may be brought into communication with the discharge-pipe 16.

On the extremity of the stem 17 is a lever or handle, 25, for operating it, and the head of the casing 14 is marked with a scale, as shown 60 in Fig. 2, so that a pointer, 31, on the valve-stem indicates by appropriate marks on the scale the effect upon the brakes when the valve is in different positions.

The operation is as follows: By turning the 65 lever or handle 25 so as to bring the index 31 to the point on the scale marked in the present

illustration "2,000," the port 19 being brought in register with the pipe 6, the steam will be caused to act upon the piston in the smaller motor-cylinder, 1, thereby applying, say, two thousand pounds pressure to the brakes. By turning the handle 25 till the index 31 reaches the point marked "4,000," the first end of the port 21 being brought in register with the pipe 7, while the port 19 is closed, the steam will be 70 introduced into the larger cylinder, 2, thus applying, say, four thousand pounds pressure to the brakes. By turning the handle 25 farther, so that the index reaches the point marked "6,000," the ports 20 and 21 are both brought 75 in register with the respective pipes 6 and 7, thus applying steam to both cylinders 1 and 2, so as to act upon the sum of their areas. Steam is in each case delivered through the port 23 to the train-brake. By turning the 80 handle still farther, to the point marked "off," the connecting-groove 24 will be brought in register with all the pipes 6, 7, 8, and 16, letting off the steam from both cylinders 1 and 2, and also the steam from the train-brakes, 85 where pressure-brakes are used therefor, thus 90 releasing all the brakes.

A suitable connection may be used to admit steam to the chamber 4 through the pipe 28 at the time the chambers 1 and 2 are emptied, or 95 the brakes may be retracted by springs, as usual. The rear end of the cylinder 2 may be open to the atmosphere, and that of the cylinder 1 also, if steam be not used for retracting.

The arrangement of the outlets in the valve-casing and valve-cylinder may of course be transposed without changing the invention, the ports in the valve proper being in a longitudinal line, and the openings in the casing 14 arranged spirally or in different angular positions. 100

In the drawings I have shown, for the purpose of illustration, two motor-cylinders having each a pipe opening into the live-steam side of its piston-chamber, and the cock with 110 a corresponding number of openings communicating through the said pipes with the interiors of the two cylinders. It will be evident, however, that the number of cylinders need not be limited to two, but any number may be 115 used, and a corresponding number of openings provided in the cock, such openings being arranged substantially as in the case of the number here shown, for the purpose of producing a cumulative pressure upon the wheels. 120

Having thus described my invention, the following is what I claim as new therein and desire to secure by Letters Patent:

1. In fluid-brakes, a cock having several outlets arranged for separate and joint use, substantially as described. 125

2. A cock constructed with ports for the delivery of steam to differential cylinders of the locomotive-brake, a port to actuate the train-brake, and a discharge-port. 130

3. The combination of a locomotive-brake and an air or vacuum train-brake actuated

simultaneously by a cock or valve common to both, substantially as set forth.

4. In fluid-brakes, the combination, with a cock having several outlets arranged for separate and joint use, of a series of motor-cylinders corresponding in number with the openings in the said cock, and arranged to be used either singly or jointly to gain several degrees of force in the application of the brakes while the motor-fluid is derived from a reservoir with a single degree of pressure.

5. In fluid-brakes, the combination, with a cock having several outlets arranged for separate and joint use, of a series of motor-cylinders corresponding in number with the openings in the said cock, and arranged to be used either singly or jointly, and a hydraulic cylinder for transmitting force by means of water- rods to the braking apparatus.

20 6. In a fluid-brake apparatus, the cylinder 14, provided with the inlet-pipe 15, discharge-pipe 16, and outlet-pipes 6, 7, and 8, in combination with the valve-stem 17 and its shell 18, provided with openings 19 20, elongated openings 21 22, arranged substantially as described, and the groove 24, as and for the purposes specified.

7. In fluid-brakes, a series of motor-cylinders of different relative internal areas arranged in line, each pair of cylinder-chambers

being separated at their contiguous ends by a single head, and each of said cylinders being provided with a pipe opening into the live-steam side of its piston-chamber, in combination with a piston-rod common to all the cylinders and carrying a series of pistons corresponding in number with the several cylinders and each of equal diameter to the internal diameter of its respective cylinder-chamber, substantially as and for the purposes described.

35 8. In fluid-brakes, the combination, with a series of motor-cylinders of differential relative internal areas, arranged in line and each provided with a pipe opening into the live-steam side of its piston-chamber, and a hydraulic cylinder in line with the steam-cylinders, and provided with a water-rod communicating with the brake-operating mechanism, of a piston-rod common to the motor-cylinders and the hydraulic cylinder and carrying a series 45 of pistons corresponding in number to the motor-cylinders, and each of equal diameter to the internal diameter of its respective cylinder-chamber, and a hydraulic piston working in the hydraulic cylinder-chamber, substantially as and for the purposes specified.

50 DOLPHUS TORREY.
